CIRCUIT CONTROLLER

Gordon F. Sauers, Pittsburgh, Pa., assignor to Westinghouse Electric & Manufacturing Company, East Pittsburgh, Pa., a corporation of Pennsylvania

Application October 9, 1941, Serial No. 414,292

16 Claims. (Cl. 200—169)

This invention relates generally to electric switching devices, and more particularly, to selective switching devices.

Where for the purpose of obtaining continuity of service, a plurality of feeder lines may be available for supplying a station bus structure or the like, it is important from the standpoint of synchronization and safety considerations that the transfer from one feeder to another should not be accomplished too quickly.

One object of this invention is to provide a novel transfer switch means which requires that the transfer switch be stopped at an intermediate open circuit position, during a transfer operation.

Another object of this invention is to provide a novel means for releasably locking a disconnecting switch in an open circuit position and in a closed circuit position.

Another object of this invention is to provide a novel transfer switch of the type described wherein during a transfer operation it is required that the operator stop the switch at an intermediate open circuit position, and perform another operation before the transfer operation can be completed.

Another object of this invention is to provide a transfer switch with novel means for locking the switch in its closed circuit position and in an open circuit position.

These and other objects of this invention will become more apparent upon consideration of the following detailed description of a preferred embodiment thereof when taken in connection with the attached drawings, in which:

Figure 1 is a longitudinal sectional view of an enclosed switch structure embodying the invention, with the switch and operating mechanism shown in elevation;

Fig. 2 is a view similar to Fig. 1 but taken at right angles to the section of Fig. 1;

Fig. 3 is an enlarged view of a portion of the switch operating mechanism; and

Fig. 4 is a section taken substantially on the line IV—IV of Fig. 3.

Although the invention will be hereinafter particularly disclosed in connection with a three-phase enclosed switching unit, it will be obvious that the invention is also capable of use with a single switch, or with any number of gang-operated switches. Certain aspects of the invention may also be useful in switches which are not enclosed.

Referring more particularly to the drawings, there is shown in Figs. 1 and 2 a switch enclosure 2 which may be of sheet metal or the like and

includes front and rear walls 4 and 6, and end walls 8 and 10. The top and bottom walls of the enclosure are not shown, because they are not essential to an understanding of this invention. 5 Front wall 4 is provided with a door 5 which may be movably secured on front wall 4 in any desired manner. Within the switch enclosure 2 there is provided a pair of supporting partitions, the upper one 14 being secured to an angle iron support 18 which, in turn, is secured to the walls of the enclosure, for example, as by welding or the like. The lower supporting partition 12 is mounted similar to the upper partition 14 on an angle iron support 16, also secured to the walls of the enclosure. The upper supporting partition 14 is provided with spaced pairs of spaced apertures, for receiving insulators 20, each of which is provided with an annular supporting flange 21 formed on a collar secured substantially at the center of the insulators, so that the insulators may be supported in the apertures of partition 14 by having flanges 21 thereof bolted, or otherwise secured to the partition 14. Each of the insulators 20 supports at its lower end, a break terminal or contact 22, and as shown in Fig. 1, the break contacts of each pair of insulators 20 are directed angularly towards each other, for a purpose to be hereinafter described. Each break contact 22 is provided with an integral stem extending through 10 a longitudinal central aperture through its associated insulator 20, and this stem is provided with a threaded outer end 24 for receiving a clamping nut 26, to secure the jaw in operative position fixed relative to its insulator. Nuts 28 may be 15 also provided for the threaded stem of the break contacts for the purpose of securing a conductor thereto for electrically connecting the contact in a circuit.

The partition 12 is provided with a row of substantially centrally located apertures for receiving insulators 30 similar to insulators 20, with the insulators positioned immediately below a pair of insulators 20 and positioned substantially intermediate the insulators 20 and break jaws 22. Each insulator 30 is also provided with a flanged collar 32 similar to the flanged collar 21 on insulators 20, for the purpose of securing the insulators to supporting partition 12. Insulators 30 support hinge contacts 34 at their upper end, and these contacts, like the break contacts 22, are provided with integral stems extending through insulators 30 and having threaded outer portions 36 for receiving a securing nut 38, and conductor clamping nuts 40.

A split blade 42 is adapted to be pivotally

mounted on each hinge contact 34 and since each blade comprises spaced side portions 44, these may be positioned on opposite sides of the hinge contact and pivotally secured thereto, for example, as by a bolt 46 having resilient cup-shaped washers 48 engaging the blade sides 44 for maintaining the blade sides in pressure engagement with the hinge contact. The blade 42 may also be provided with limited area contact surfaces for engaging the hinge contact 34, as well as 10 break contacts 22, and these may assume the form shown, for example, in the copending application of H. J. Crabbs, Serial No. 268,906, filed April 20, 1939, and issued November 11, 1941 as Patent No. 2,262,168 to the same assignee of this 15 application. The specific construction of split blade 42 and the manner in which it is secured to hinge contact 34, and the manner in which the other ends of the blade sides are secured together by bolt 50 and washers 52, are similar to that disclosed in the above-mentioned Crabbs patent, and accordingly, for more complete description of these parts, reference is hereby made to the aforesaid patent.

As shown, the upper end of blade 42 is in a position intermediate one pair of break contacts 22, and it will be apparent that by pivotal movement of blade 42 about its pivot 46 on the hinge contact, the upper end thereof may be moved into engagement with either one of break jaws 22 shown in Fig. 1. The break jaws are provided with notches 54 for receiving the portion of bolt 50 connecting the outer ends of blade sides 44.

A switch actuating shaft 56 is preferably mounted adjacent front wall 4 of the switch enclosure and is adapted to extend the entire length of the enclosure to be mounted in bearings 57 at opposite ends thereof, which bearings are secured to end walls 8 and 10 of the enclosure by brackets 59. Bearings 57 may be bolted to the 40 brackets as shown, and the brackets may be secured to the casing walls by welding or the like. On the end of shaft 56 adjacent end wall 10, there is secured an operating casting 60 fixed to rotate with the shaft, and as shown is preferably 45 in the shape of a circular segment. The operating casting 60 is preferably of a size so that in all positions of the switch a portion of the circular periphery of the block projects through an opening 58 provided in door 5. There is also mounted on actuating shaft 56 at points substantially opposite each of switch blades 42, a crank 61 rigidly secured to the shaft. The crank 61 may comprise separate threaded engageable parts for providing longitudinal adjustment 55 thereof to obtain simultaneous movement of the blades into and out of engagement with their respective break contacts. The outer ends of cranks 61 are connected to blades 42, respectively, by connecting links 62 of insulating material, 60 such for example, as fiber or the like, which are pivoted to the cranks as at 63, and to the mid-portion of blade 42 as at 64, with the link received between the sides of the split blade.

Operating casting 60 is provided with a pair 65 of substantially radially extending bores 68 and 70 providing sockets for receiving an actuating handle. Each socket is provided with a reduced inner end portion 72 terminating short of actuating shaft 56, and adjacent the reduced portion 70 of the bores, there is provided a lateral opening 74 in the plane of the bores, and elongated for a short distance in the direction of the bores. These lateral slots 74 are for the purpose of slidably receiving locking pins or lugs 76 extending 75

laterally through slots 74 and having collars 78 fixed thereto, by any suitable means, and positioned on opposite sides of the operating casting 60 to prevent endwise movement of the pins relative to the block. As shown in Figs. 2 and 4, one end of pins 76 is extended considerably beyond the side of the operating casting adjacent wall 4 as at 79, so as to be engageable with a fixed stop projection 82 mounted on wall 4, when the pins are in their outermost position. Pins 76 are normally biased to their outermost position in slots 74, by coil compression springs 80 engageable between pins 76 and the bottom of reduced portion 72 of the bores.

With the structure provided in an intermediate open circuit position, as shown in Fig. 1 of the drawings, wherein the blade 42 is intermediate the pair of break contacts associated therewith, if it is desired to move blade 42 to the right into engagement with one break contact 22, it will be necessary to insert operating handle 84 into bore 70 of the mounting block to thereby move the locking pin 76 in the bore inwardly against the bias of spring 80 and remove it from engagement with fixed stop projection 82. As soon as the pin 76 in bore 70 clears stop 82, the handle may be moved upwardly or in a clockwise direction, as shown in Fig. 1, to thereby move actuating shaft 56, crank 61, and consequently, blade 42, in a similar direction until the blade engages the break contact on the right. Movement of blade 42 into engagement with each break contact 22 is limited by adjustable stop bolts 63 positioned to engage opposite edges of the casting, in its extreme positions corresponding to the extreme positions of blade 42 in engagement with break contacts 22, respectively, to prevent damage to the contacts and operating mechanism. When handle 84 is removed from bore 70 the switch will be locked in this position because pin 76 will be positioned above stop projection 82.

Now, if it is desired to move the blade from engagement with the break contact 22 on the right into engagement with the break contact 22 on the left, as viewed in Fig. 1, it is necessary that the operating handle 84 be inserted in bore 70 to push back the pin 76 associated therewith clear of projection 82 and the blade may then be moved to the intermediate position shown in Fig. 1. Operating handle 84 will then have to be removed and inserted in bore 68 to move pin 76 in this bore inwardly enough to clear stop 82 and permit movement of the mounting block downwardly below the position shown in Fig. 1. Considering the blade 42 to be in engagement with the break contact 22 at the right, as viewed in Fig. 1, it is impossible to move the blade into engagement with the other break contact without stopping at an intermediate position because it is essential that operating handle 84 be in bore 70 to release blade 42. Thereafter, movement of the blade from engagement with break contact 22 on the right towards the other break contact will be halted by engagement of the pin 76 in bore 68 as soon as the position shown in Fig. 1 is reached. It will thereupon be necessary to remove the handle from bore 70 and insert it in bore 68 in order to move the blade into engagement with break contact 22 at the left as described above.

In view of the foregoing, it is obvious that this invention prevents operation of a switch of the double-throw type from engagement with one set of contacts into engagement with another set of

contacts without requiring that the switch be stopped at a position intermediate the contacts to change the mounting of the operating handle. This will clearly prevent rapid transfer of the switch blade from one set of contacts to another, and will also require a predetermined amount of time to complete a transfer operation, to thereby give the operator an opportunity to check the transfer operation while he is performing it. This delay required in the transfer operation with the switch of this invention is, as previously pointed out, especially important when switching from one feeder line to another, because it gives synchronous apparatus an opportunity to come to a standstill before switching to another feeder which may be out of synchronism with the first feeder. Furthermore the same means is utilized to lock the switch blade in engagement with each contact. The structure by which the desired objects are accomplished is particularly simplified and efficient, in that but few operating parts are required to obtain the desired results.

Having described a preferred embodiment of the invention in accordance with the patent statutes, it is desired that the invention be not limited to this particular embodiment, because it will be obvious, particularly to those skilled in the art, that many modifications and changes may be made in this embodiment without departing from the broad spirit and scope of the invention. Therefore, it is desired that the invention be interpreted as broadly as possible and that it be limited only as required by the prior art.

I claim as my invention:

1. In a switch, a pair of spaced contact means, movable contact means adapted to be moved into and out of engagement with said spaced contact means, respectively, means for locking said movable contact means at a position intermediate said spaced contact means, said locking means including parts for preventing movement of said movable contact means in opposite directions, respectively, actuating means adapted to be removably associated with said movable contact means in two different positions and cooperable with said parts of said locking means in said different positions, respectively, whereby when said actuating means is associated with said movable contact means in one position, it is operative to release said locking means to permit actuation of said movable contact means only between said intermediate position and a position wherein said movable contact means is in engagement with one of said spaced contact means, and when said actuating means is associated with said movable contact means in the other of its different positions it is operative to release said locking means to permit actuation of said movable contact means only between said intermediate position and the position wherein said movable contact means is in engagement with the other of said spaced contact means.

2. In a switch, a pair of spaced contact means, movable contact means adapted to be moved into and out of engagement with said spaced contact means, respectively, latch means biased to latching position for releasably latching said movable contact means at a position intermediate said spaced contact means, said latch means including separate latch elements preventing movement of said movable contact means in opposite directions, respectively, actuating means adapted to be removably associated with said movable contact means in two different positions and cooperable with said latch elements in said

different positions, respectively, whereby when said actuating means is associated with said movable contact means in one position, it is operative to release said latch means to permit actuation of said movable contact means only between said intermediate position and a position wherein said movable contact means is in engagement with one of said spaced contact means, and when said actuating means is associated with said movable contact means in the other of its different positions it is operative to release said latch means to permit actuation of said movable contact means only between said intermediate position and the position wherein said movable contact means is in engagement with the other of said spaced contact means.

3. In a switch, a pair of spaced contact means, movable contact means adapted to be moved into and out of engagement with said spaced contact means, respectively, means for locking said movable contact means at a position intermediate said spaced contact means including a relatively fixed projection and a pair of spaced movable locking lugs associated with said movable contact means for movement therewith and biased to positions wherein their paths of movement with said movable contact means intersect said projection, so that at said intermediate position said projection will be positioned intermediate said spaced lugs, and actuating means adapted to be removably associated with said movable contact means in two different positions and cooperable with said lugs in said positions, respectively, so as to move the respective lug against its bias to clear said projection and permit movement of said movable contact means into engagement with one of said spaced contact means.

4. In a switch, a pair of spaced contact means, 40 movable contact means adapted to be moved into and out of engagement with said spaced contact means, respectively, an actuating member for said movable contact means, a relatively stationary member adjacent said actuating member, 45 a projection on one of said members and spaced retractile lugs on the other of said members with said lugs normally positioned to lie on opposite sides of said projection in a position of said movable contact means intermediate said spaced contact means to lock the parts in such intermediate position, means biasing said lugs to their normal positions, spaced mounting means on said actuating member for removably mounting an operating handle thereon at a plurality of different positions, said mounting means located relative to said lugs in a manner such that when said operating handle is mounted at one of said positions it is effective to retract one of said lugs, and when mounted at another of said positions it is effective to retract the other of said lugs.

5. In a switch, a pair of spaced contact means, movable contact means adapted to be moved into and out of engagement with said spaced contact means, respectively, an actuating member for said movable contact means, a relatively stationary member adjacent said actuating member, a projection on one of said members and spaced retractile lugs on the other of said members with said lugs normally positioned to lie on opposite sides of said projection in a position of said movable contact means intermediate said spaced contact means to lock the parts in such intermediate position, means biasing said lugs to their normal positions, spaced bores ex-

tending into said actuating member for removably mounting an operating handle thereon at a plurality of different positions, said bores constructed and located relative to said lugs in a manner such that when said operating handle is mounted at one of said positions it is effective to retract one of said lugs, and when mounted at another of said positions it is effective to retract the other of said lugs.

6. In a switch, a pair of spaced contact means, movable contact means adapted to be moved into and out of engagement with said spaced contact means, respectively, a movably mounted actuating member for said movable contact means, a relatively fixed projection, retractible lugs on said actuating member with said lugs normally positioned to lie on opposite sides of said projection in a position of said movable contact means intermediate said spaced contact means to lock the parts in such intermediate position, means biasing said lugs to their normal positions, spaced mounting means on said actuating member for removably mounting an operating handle thereon at a plurality of different positions, said mounting means located relative to said lugs in a manner such that when said operating handle is mounted at one of said positions it is effective to retract one of said lugs, and when mounted at another of said positions it is effective to retract the other of said lugs.

7. In a switch, a pair of spaced contact means, movable contact means adapted to be moved into and out of engagement with said spaced contact means, respectively, a movably mounted actuating member for said movable contact means, a relatively fixed projection, retractible lugs on said actuating member with said lugs normally positioned to lie on opposite sides of said projection in a position of said movable contact means intermediate said spaced contact means to lock the parts in such intermediate position, means biasing said lugs to their normal positions, spaced bores extending into said actuating member for removably mounting an operating handle thereon at a plurality of different positions, said bores constructed and located relative to said lugs in a manner such that when said operating handle is mounted at one of said positions in one of said bores it is effective to retract one of said lugs, and when mounted at another of said positions in another of said bores it is effective to retract the other of said lugs.

8. In a switch, a pair of spaced contact means, movable contact means adapted to be moved into and out of engagement with said spaced contact means, respectively, a movably mounted actuating member for said movable contact means, a relatively fixed projection, retractible lugs on said actuating member with said lugs normally positioned to lie on opposite sides of said projection in a position of said movable contact means intermediate said spaced contact means to lock the parts in such intermediate position, means biasing said lugs to their normal positions, spaced bores extending into said actuating member for removably mounting an operating handle thereon at a plurality of different positions, said bores having lateral openings to receive parts associated with said lugs, respectively, whereby when said operating handle is mounted at one of said positions it is effective to retract one of said lugs, and when mounted at another of said positions it is effective to retract the other of said lugs.

9. In apparatus of the type described, a plu-

rality of switches each of which includes spaced contacts and a movable contact means adapted to be moved into and out of engagement with said spaced contacts, respectively, common actuating means for said switches including a movably mounted actuating member operatively associated with said movable contact means, mounting means movable with said actuating member and having spaced mountings for removably securing an operating handle in different positions, locking means cooperable with said mounting means to lock said movable contact means in a position intermediate said spaced contacts, said locking means including parts for preventing movement of said movable contact means in opposite directions, respectively, said handle cooperable with said parts of said locking means in said different positions, respectively, whereby when said handle is associated with said mounting means in one position it is operative to release said locking means to permit actuation of said movable contact means only between said intermediate position and a position wherein said movable contact means is in engagement with one of said spaced contact means, and when said handle is associated with said mounting means in the other of its different positions it is operative to release said locking means to permit actuation of said movable contact means only between said intermediate position and the position wherein said movable contact means is in engagement with the other of said spaced contact means.

10. In apparatus of the type described, a plurality of switches each of which includes spaced contacts and a movable contact means pivotally mounted for movement into and out of engagement with said spaced contacts, respectively, a common operating shaft for said switches operatively associated with said movable contact means, mounting means on said shaft and having spaced mountings for removably securing an operating handle in different positions, locking means cooperable with said mounting means to lock said movable contact means in a position intermediate said spaced contacts, said locking means including parts for preventing movement of said movable contact means in opposite directions, respectively, said handle cooperable with said parts of said locking means in said different positions, respectively, whereby when said handle is associated with said mounting means in one position it is operative to release said locking means to permit actuation of said movable contact means only between said intermediate position and a position wherein said movable contact means is in engagement with one of said spaced contact means, and when said handle is associated with said mounting means in the other of different positions it is operative to release said locking means to permit actuation of said movable contact means only between said intermediate position and the position wherein said movable contact means is in engagement with the other of said spaced contact means.

11. In a switch, a pair of spaced contact means, movable contact means adapted to be moved into and out of engagement with said spaced contact means, respectively, an actuating member for said movable contact means, an enclosure for said switch having an opening for rendering said actuating member accessible, cooperating locking means on said actuating member and enclosure for locking said movable contact means in a position in-

termmediate said spaced contact means, said locking means including parts for preventing movement of said movable contact means in opposite directions, respectively, said actuating member having spaced handle mountings for receiving an actuating handle in different positions, said handle cooperable with said parts of said locking means in said different positions, respectively, whereby when said handle is associated with said actuating means in one position it is operative to release said locking means to permit actuation of said movable contact means only between said intermediate position and a position wherein said movable contact means is in engagement with one of said spaced contact means, and when said handle is associated with said actuating means in the other of its different positions it is operative to release said locking means to permit actuation of said actuating means only between said intermediate position and the position wherein said actuating means is in engagement with the other of said spaced contact means.

12. In a switch, a pair of spaced contact means, movable contact means adapted to be moved into and out of engagement with said spaced contact means, respectively, an actuating member for said movable contact means, an enclosure for said switch having an opening for rendering said actuating member accessible, said actuating member constructed to substantially close said opening and including a portion projecting through said opening, cooperating locking means on said actuating member and enclosure for locking said movable contact means in a position intermediate said spaced contact means, said locking means including parts for preventing movement of said movable contact means in opposite directions, respectively, said projecting portion of said actuating member having spaced handle mounting sockets for receiving an actuating handle in different positions, said handle cooperable with said parts of said locking means in said different positions, respectively, whereby when said handle is associated with said actuating means in one position it is operative to release said locking means to permit actuation of said movable contact means only between said intermediate position and a position wherein said movable contact means is in engagement with one of said spaced contact means, and when said handle is associated with said actuating means in the other of its different positions it is operative to release said locking means to permit actuation of said actuating means only between said intermediate position and the position wherein said actuated means is in engagement with the other of said spaced contact means.

13. In a switch, a pair of spaced contact means, movable contact means adapted to be moved into and out of engagement with said spaced contact means, respectively, a pivotally mounted actuating member for said movable contact means, an enclosure for said switch having an opening for rendering said actuating member accessible, said actuating member including a circular peripheral portion adapted to extend at least in part through said enclosure opening, cooperating locking means on said actuating member and enclosure for locking said movable contact means in a position intermediate said spaced contact means, said locking means including parts for preventing movement of said movable contact means in opposite di-

rections, respectively, said actuating member having spaced handle sockets opening to the portion of said member exteriorly of said enclosure for receiving an actuating handle in different positions, said handle cooperable with said parts of said locking means in said different positions, respectively, whereby when said handle is associated with said actuating means in one position it is operative to release said locking means to permit actuation of said movable contact means only between said intermediate position and a position wherein said movable contact means is in engagement with one of said spaced contact means, and when said handle is associated with said actuating means in the other of its different positions it is operative to release said locking means to permit actuation of said actuating means only between said intermediate position and the position wherein said actuating means is in engagement with the other of said spaced contact means.

14. In a switch, a pair of spaced contact means, movable contact means adapted to be moved into and out of engagement with said spaced contact means, respectively, a movably mounted actuating member for said movable contact means, a relatively fixed projection, retractile lugs on said actuating member with said lugs normally positioned to lie on opposite sides of said projection in a position of said movable contact means intermediate said spaced contact means to lock the parts in such intermediate position, spaced bores extending into said actuating member for removably mounting an operating handle thereon at a plurality of different positions, said bores having lateral openings for slidably receiving an end of said lugs, resilient means in said bores for biasing said lugs to their normal positions, whereby when said operating handle is mounted at one of said positions, it is effective to retract one of said lugs, and when mounted at another of said positions, it is effective to retract the other of said lugs.

15. In a switch, a pair of spaced contact means, movable contact means adapted to be moved into and out of engagement with said spaced contact means, respectively, means for locking said movable contact means at a position intermediate said spaced contact means, actuating means adapted to be removably associated with said movable contact means in two different positions and cooperable with different portions of said locking means in said different positions, respectively, whereby when said actuating means is associated with said movable contact means in one position, it is operative to release said locking means to permit actuation of said movable contact means only between said intermediate position and a position wherein said movable contact means is in engagement with one of said spaced contact means, and when said actuating means is associated with said movable contact means in the other of its different positions it is operative to release said locking means to permit actuation of said movable contact means only between said intermediate position and the position wherein said movable contact means is in engagement with the other of said spaced contact means.

16. In a switch, a pair of spaced contact means, movable contact means adapted to be moved into and out of engagement with said spaced contact means, respectively, means for locking said movable contact means at a posi-

tion intermediate said spaced contact means and at spaced positions wherein said movable contact means is in engagement with said spaced contacts, respectively, including a relatively fixed projection and a pair of spaced movable locking lugs associated with said movable contact means for movement therewith and biased to positions wherein their paths of movement with said movable contact means intersects said projection, so that at said intermediate position said projection will be positioned intermediate said spaced lugs and at spaced positions wherein said movable contact means engages said spaced

contact means, both lugs will be positioned at opposite sides of said projection, respectively, to prevent disengagement of said contact means, and actuating means adapted to be removably associated with said movable contact means in two different positions and cooperable with said lugs in said positions, respectively, so as to move the respective lug against its bias to clear said projection and permit movement of said movable contact means into and out of engagement with one of said spaced contact means.

GORDON F. SAUERS.
